UNITED STATES PATENT OFFICE.

CHARLES M. ANDERSON, OF WATERLOO, IOWA.

TEAT-CUP FOR MILKING-MACHINES.

1,312,941.

Specification of Letters Patent. Patented Aug. 12, 1919.

Application filed July 12, 1917. Serial No. 180,119.

To all whom it may concern:

Be it known that I, CHARLES M. ANDERSON, citizen of the United States of America, and resident of Waterloo, Blackhawk county, Iowa, have invented certain new and useful Improvements in Teat-Cups for Milking-Machines, of which the following is a specification.

My invention relates to improvements in teat-cups for milking machines. My improvement consists in constructing a resilient teat-cup in such a manner as to most efficiently operate in the milking operation by exercising under the combined actions of interior air-suction and exterior air-pressure a stripping of the inclosed teat simulating the natural method.

This object I have accomplished by the means which are hereinafter described and claimed, and which are illustrated in the accompanying drawings, in which Figure 1 is a central longitudinal section of an elastic teat-cup and its rigid housing; Fig. 2 is an elevation, in partial section, of the same structures, showing in full and in dotted lines different positions of the resilient cup; Fig. 3 is a plan of the teat-receiving end of said device; Fig. 4 is a transverse section of the resilient cup alone on the line 4—4 of said Fig. 1; Fig. 5 is a transverse section of both said cup and its housing taken on the line 5—5 of said Fig. 2, showing the cup deflated, and Fig. 6 is a transverse section of the same parts taken on the line 6—6 of said Fig. 2, showing the cup deflated at a place farther from its teat-receiving end.

Similar numerals of reference denote corresponding parts throughout the several views.

My improved resilient teat-cup 6 is of lengthened conical form with relatively thin walls except as hereinafter mentioned. The cup 6 is contained within a rigid housing 1 of somewhat larger interior diameter and which has an inlet-tube 8 used to convey compressed air thereinto from an air-compressing apparatus not shown.

The wider end of said housing has an outer integral annulus 2 exteriorly-threaded to receive a ring-nut 3, the latter having an inwardly-directed flange adapted to clamp between itself and said annulus a widened inverted terminal ring on the teat-receiving end of the inclosed cup 6. A conical hollow mouth-piece or liner 5 is mounted fittingly

within the opposite narrowed end of the teat-cup, extending outwardly therefrom and having exterior threads on its outer portion to receive an interiorly-threaded stem 4, the latter adapted to have an end of 60 an elastic hose or tube slipped over it. When screwed upon the liner 5, the widened end of the stem 4 engages the adjacent end of the housing 1, drawing the conical part of said liner against the surrounding end portion of 65 the teat-cup to firmly compress it against the housing and thus securing all said parts firmly together.

The teat-cup 6 is constructed with a plurality of longitudinally arranged thickened 70 portions or ribs 7 separated by the thinner intermediate parts of the cup walls, which as shown where three such ribs are employed gives the body of the cup a triangular cross-section. The concavities or outer troughs 75 of the ribs 7 as shown in Fig. 1, supply spaces between the cup 6 and the housing 1 at these locations which gradually widen outwardly toward the teat-receiving end of the cup. Because of this, when air under 80 compression is introduced through the inlet-tube 8 into said interspace, the teat-receiving end of the cup will be collapsed first. This action is displayed in said Fig. 2, where the full lines show the first part of the action where the teat-receiving end of the cup 85 is first collapsed, and where the dotted lines depict the continued action of the compressed air in successively collapsing the rest of the cup 6. This operation causes a gradual stripping of the milk from the teat beginning at the root of the teat next the udder and continuing progressively toward its tip. This simulates the natural action and suction of a calf's mouth and jaws, and 90 thoroughly strips the teat with a minimum of discomfort to the animal. When three ribs 7 are used, neither is directly opposed to another, but all of them draw together to 95 compressively surround the teat, the intermediate thinner portions of the teat-cup walls yielding as shown in Figs. 5 and 6, whereby the teat is compressed from different directions beginning near the udder, the suction derived from an air-pump connected to the stem 4 exhausting the air from 100 said cup and withdrawing the milk from the teat. The teat-receiving end of the teat-cup 105 6 is inverted outwardly, and forms a resilient raised hollow annulus part extending 110

beyond the metal clamping-ring 3. Because of this, no metal comes into direct contact with either the teat or the udder of an animal, which in very cold weather, is much 5 conducive to the animal's comfort.

It should be noticed that the part 4 as a nut causes the conical receiver 5 to tightly clamp the teat-cup between itself and the housing 1, forming an air-tight joint. The 10 whole hollow of the teat-cup and the communicating receiver 5 thus presents a tight structure, where no leakage can occur, and which renders the device easily cleaned and sanitary.

15 Having described my invention, what I

claim as new, and desire to secure by Letters Patent, is:

1. A teat-cup of elastic material, shaped with three like broad relatively thick longitudinal portions connected by narrow relatively thin wall parts. 20

2. A teat-cup of elastic material shaped with three like broad relatively thick longitudinal portions, each gradually narrowed from its medial part toward the abutting wall portions on either side, to collapse with a triform cross-section. 25

Signed at Waterloo, Iowa, this 25th day of June, 1917.

CHARLES M. ANDERSON.
